UNITED STATES PATENT OFFICE.

ERNEST B. GURGANIOUS, OF ROCHESTER, MINNESOTA.

WELL-DRILLING RIG.

Application filed February 20, 1926. Serial No. 89,786.

This invention relates to an improvement in well drilling rigs.

The purpose of the invention is to provide a chain drive for the bull-wheel of well drilling rigs, thus eliminating the usual rope-drive for this bull-wheel. These wheels are usually driven by a long rope which is stretched from the band-wheel at the front of the drilling rig and, in order to 10 drive the bull-wheel in a direction opposite to that of the band-wheel, it is necessary to cross the rope in the center. A certain amount of slack must also be left in the rope and these various things cause considerable 15 annoyance and difficulty in using a rope, and, even loss of life at times.

In my improved construction, these drive ropes are eliminated and suitable sprocket chains are provided for driving the bull-wheel from the band-wheel. By providing 20 reverse gearing at a point in this chain drive, the bull-wheel may thereby be driven in a direction opposite to that of the band-wheel. Suitable clutches are also provided for connecting the chain to the respective driving 25 and driven wheels.

Various other improvements are also provided for the drilling rig, such as a novel manner of clamping the disks constituting 30 the drum on the bull-wheel shaft and a novel form of brake, especially constructed and adapted for the bull-wheel, and also, a very practical and useful form of chain guide or 35 tightener is provided for supporting the drive chain at points intermediate its ends. These and various other improvements will be more fully set forth hereafter.

In the accompanying drawings:—

Fig. 1 is a side elevation of my improved 40 well drilling rig;

Fig. 2 is a top plan view of the same;

Fig. 3 is a transverse sectional view on the 45 line 3—3 of Fig. 2;

Fig. 4 is a transverse sectional view on the line 4—4 of Fig. 2;

Fig. 5 is a side elevation partly in section 50 of one of the disks for the rope spool;

Fig. 6 is an edge view of the same;

Fig. 7 is a top plan view of the same disk;

Fig. 8 is a plan view of the reverse gearing;

Fig. 9 is a side elevation partly in section 55 of the same;

Fig. 10 is a detail view partly in section of the brake-applying segment;

Fig. 11 is a side elevation of the chain support; and

Fig. 12 is a top plan view of the same.

Referring more particularly to Figs. 1 and 2, the numeral 1 indicates the front standards of the derrick, which are mounted upon the main sills 2, which, in turn, are supported by the transverse mud-sills 3, and sub-sills may be placed beneath the mud-sills 3 which support the derrick. As shown 60 in Fig. 1, the bull-wheel which carries the rope or cable is ordinarily mounted in the standards 1 of the derrick in a position to allow the rope to be wound therefrom and up over the crown block at the top of the 65 derrick and then down into the well, being connected with the rocking beam at a suitable point in the derrick, in order to impart a reciprocating or impact motion to the rope and to the tools carried thereby. The bull- 70 wheel is adapted to be driven from a band-wheel shown at the left in Fig. 1 and, in the ordinary practice, a crossed rope imparts the motion from the band-wheel to the 75 bull-wheel, but, in my improved construction, chains are provided for this purpose, 80 thus eliminating the undesirable and dangerous rope drive. The band-wheel may be driven from a suitable engine placed at a 85 distance therefrom and usually at a point outside of the drill house.

As shown more particularly in Fig. 3, a non-rotatable shaft 5 is mounted in suitable bearings in the standards 1 of the derrick. Mounted upon this shaft 5 are suitable bushings 6, which support the outer ends of the sleeve 7 and are keyed to this sleeve in order to turn therewith upon the shaft 5. Oil cups 8 are provided in the sleeve 7, which register with oil ducts in the bushings 6, in 90 order to supply a lubricant to the bearing surface of these bushings upon the shaft 5. Interposed between one end of the sleeve 7 and the adjacent standard 1 is a suitable bearing-block 10, over which passes a long 100 U-bolt 9, the lower end of which extends beneath the back-framer sills 3' and nuts 12 are secured onto the ends of this U-bolt for the purpose of holding the end of the shaft 5 down in its proper position and in order 105 not to cause any unnecessary bearing of this shaft in an upward direction, because of its vibration.

The opposite end of the shaft 5 is also provided with a bearing-block 13 for receiv- 110

ing the long U-bolt 14, which is similarly connected beneath the back-framer sill 3' by the nuts 15.

As shown in Fig. 3, a brake drum 16 is keyed to the sleeve 7 and is provided with a peripheral groove 17 which receives the brake-band 18. As shown in Fig. 10, the opposite ends of the brake-band 18 are connected by means of suitable brackets 19 to the eye-bolts 20, preferably three in number, through which the pins 21 pass and hold these eye-bolts suitably positioned between the disks 22 of the brake-segment 23. This brake-segment 23 is keyed upon a stub-shaft 24, which has its opposite ends received in suitable boxes 25. One end of this shaft 24 extends through its respective box and is made hexagonal to receive an operating lever 26 which is held in place by means of a washer and screw 27. A metal disk 28 is bolted to the inside of the brake-drum 16 by means of the bolts 29, as shown in Fig. 3. This disk is adapted to hold the rope and rope-drum away from the brake-drum.

The opposite end of the sleeve 7 has a wheel 30 keyed thereon which is also provided with a disk 31, bolted to the spokes thereof, in a manner similar to the disk 28 and for the same purpose. A bushing 32 is secured to the shaft 5 by means of the set-screws 33 for the purpose of limiting the endwise movement of the sleeve 7 and wheels carried thereby relative to this shaft. The wheel 30 has a clutch-drum 34 secured thereto by means of the bolts 35 passing through the spokes, as shown in Fig. 3, and clutch-arms 36 are mounted in position to engage the periphery of the clutch-drum 34. These clutch-arms may be carried and operated by any suitable construction from the clutch-bushing 37. The usual form of clutch-fork 38 is also provided for throwing the clutch into and out of engagement with the clutch-drum 34 and for clamping the clutch-arms upon the periphery of this drum. The clutch-bushing 37 is rotatably mounted on the shaft 5 for rotating relative to this shaft and, in order to be driven, the clutch-bushing has a sprocket-wheel 39 mounted thereon. A drive-chain 41 passes over the sprocket-wheel 39 for driving this wheel and the clutch mechanism connected therewith and, whenever the clutch-arms 36 are clamped upon the clutch-drum 34, this will cause the rotation of the pulley 30 and the sleeve 7 and, through this sleeve, the brake-drum 16.

Mounted upon the sleeve 7 are suitable rope-drum disks 42 which are made in sections, to be clamped upon the sleeve 7, and these disks are provided with double headed bolts 43, which are set in through slots 44, the heads of the bolts being received in notches 45 as shown in Figs. 5 to 7. The disks 42 cooper-

ate with the sleeve 7 to form a rope drum for receiving the rope.

The usual groove 46 is provided through the periphery of each of the disks as shown in Fig. 7 for allowing the rope to be wound off of and onto the drum.

For the purpose of strengthening the sleeve 7 through the center thereof at a point where the rope drum, formed by the disks 42, is positioned, a sleeve 47 is riveted thereto by means of the rivets 48 and this sleeve 47 has inwardly extending projections 49 formed thereon, which extend toward but do not engage the shaft 5.

The sprocket-chain 41 passes over a sprocket-wheel 50 shown in detail in Fig. 8, which sprocket-wheel 50 is fixed upon a shaft 51, extending through bearings 52. The shaft 51 has a gear 53 fixed thereon which meshes with a pinion 54 carried by a shaft 55, likewise extending through bearings 56 in the case 57 and has a sprocket wheel 58 fixed thereon exteriorly of this casing 57. It will be noted that the sprocket-wheels 50 and 58 are mounted exteriorly of the casing 57 whereas the gear and pinion 53 and 54 are mounted within the casing and are adapted to be rotated in a film of oil for lubricating the same. Any suitable cover 59 may be provided for covering the gearing in the casing. The casing 57 has bolts 60 extending therethrough and through slots 61 in the supporting plate 62, mounted upon and securely bolted to the mud-sills 3. A chain 63 passes around and drives the sprocket-wheel 58, said chain extending to a double sprocket-wheel 64 mounted in a suitable supporting boxing 65. Placed intermediate of the sprocket-wheels 64 and 58 is a suitable chain support or tightener for supporting the weight of the chain through this area. This chain support may be made in any suitable construction, but as shown in Figs. 11 and 12 it is formed of a plurality of channel-irons 66 securely bolted upon transverse sills secured between the mud-sills 3. The channel-irons 66 are placed back to back as shown in Fig. 12 with a space therebetween for receiving the pillow-blocks 67. These pillow-blocks are securely held in the channel-irons 66 by means of bolts 68, passing through an elongated slot 69 formed in each flange of the channel-irons 66. This form of supporting the pillow-blocks 67 permits of adjustment of the same relative to the channel-irons for applying tension to the chain. The pillow-blocks 67 carry stub-shafts 70 upon which are mounted idler sprocket-wheels 71, for engaging the sprocket-chain and supporting the same. As shown in Fig. 11, these sprocket-wheels are placed in staggered relation so that one will engage the upper surface of the sprocket-chain while the other engages the lower surface therefor,

thus not only supporting the chains but also permitting of the application of tension thereto for taking up any slack that may exist in the chain.

5 Extending upwardly from the double sprocket-wheel 64 is a sprocket-chain 72 which passes over a sprocket-wheel 73 loosely mounted upon the band-wheel shaft 74 as shown in Fig. 4. The hub of the sprocket-wheel 73 is provided on one side with the clutch-element 75 and on the opposite side with a clutch-fork 76, for operating the sprocket-wheel to move the clutch-element 75 into engagement with a clutch-element 75', extending outwardly from the face-plates 77, of the band-wheel 78. The plates 77 are bolted together through the band-wheel by bolts 79 and each of these plates is keyed to the shaft 74 by keys 80. For the purpose of withdrawing the keys 80, the clutch-element 75 is hollowed out as at 81, in order to permit the insertion of a key withdrawing hook between the clutch-element 75' and the shaft 74.

25 The operation and function of this rig will be apparent from the foregoing description but to recapitulate, the band-wheel 78 is driven from any suitable engine or source of power, usually by a belt passing over this wheel, and this band-wheel drives the sprocket-wheel 73 whenever the clutch elements 75 and 75' are intermeshed, thus driving the sprocket-chain 72 and the double sprocket wheel 64, which, in turn, drives the sprocket-chain 63 and the sprocket-wheel 58. The sprocket-wheel 50 is driven from the sprocket-wheel 58 by means of the reversing gears 53 and 54 and this sprocket-wheel 50 drives the sprocket-chain 41, which passes 40 around the sprocket-wheel 39, driving this wheel and the clutch-arms 36, which, when clamped upon the clutch-drum 34, drives this drum and the wheel 30, thus imparting rotary motion to the sleeve 7, which carries the 45 rope-drum and the brake-drum 16.

It will be noted that the reversing gearing will drive the wheel 30 and rope-drum in a direction opposite to that of the band-wheel

78. This is preferable for the purpose of winding the cable out of the well. Whenever either of the clutches mounted on the shaft 74 or the shaft 5 is drawn out of engagement, the rope-drum may be brought to a stop by moving the brake lever 26 which tightens the brake-band 18 upon the brake-drum 16.

I claim:

1. In a well drilling rig, the combination of a band wheel, a bull wheel, a drive chain connected with and extending downward from said band-wheel, a drive chain connected with and extending downward from the bull wheel, and a connecting chain operatively connected with said downwardly extending drive chain.

2. In a well drilling rig, the combination of a bull-wheel, a drive chain connected with said bull wheel and extending downwardly substantially vertically therefrom, reverse gearing connected with said drive chain, a double chain wheel arranged in substantially the same horizontal plane as the reverse gearing, a chain connecting the double chain wheel with the reversing gearing, a driving band wheel, and a driving chain extending upwardly from the double chain wheel and connected with the band wheel.

3. In a device of the character described, the combination of a shaft, a sleeve mounted thereon, bushings interposed between the shaft and the sleeve adjacent the ends thereof, a bushing secured to the sleeve substantially at the center thereof, drum disks mounted upon said sleeve at the point of said central bushing, bearing blocks mounted upon the shaft for limiting the movement of the sleeve relative thereto, a brake-drum mounted upon one end of the sleeve, a wheel mounted upon the opposite end of the sleeve, face plates secured to the inside of the brake-drum and wheel, a clutch-drum secured to said wheel, clutch means for engaging said clutch-drum, and means for driving said clutch means.

In testimony whereof I affix my signature.

ERNEST B. GURGANIOUS.
